(57) **CLAIM**

The ornamental design for a handheld electronic device shell, as shown and described.

DESCRIPTION

FIG. 1 is a first perspective view of the handheld electronic device shell;

FIG. 2 is a second perspective view thereof;

FIG. 3 is a first elevational view thereof;

FIG. 4 is a second elevational view thereof;

FIG. 5 is a first side elevational view thereof;

FIG. 6 is a second side elevational view thereof;

FIG. 7 is a top plan view thereof;

FIG. 8 is a bottom plan view thereof;

FIG. 9 is a first perspective view of the handheld electronic device shell in another configuration;

FIG. 10 is a second perspective view thereof;

FIG. 11 is a first elevational view thereof;

FIG. 12 is a second elevational view thereof;

FIG. 13 is a first side elevational view thereof;

FIG. 14 is a second side elevational view thereof;

FIG. 15 is a top plan view thereof; and,

FIG. 16 is a bottom plan view thereof.
